(57) **CLAIM**

The composite stone with facets displayed, as shown and described.

DESCRIPTION

FIG. 1 is a perspective view of a first embodiment of this invention;

FIG. 2 is a top plan view of the first embodiment shown in FIG. 1; and,

FIG. 3 is a front plan view of the first embodiment of FIG. 1. No bottom or side views are presented as these are mirror images of FIGS. 2 and 3 respectively.

It being understood that the broken lines are for illustrative purposes only.
